THREAD-CONTROLLING MECHANISMS FOR
SEWING MACHINESArthur N. Hale, Stratford, Conn., assignor to The
Singer Manufacturing Company, Elizabeth,
N. J., a corporation of New Jersey

Application September 19, 1950, Serial No. 185,560

7 Claims. (Cl. 112—199)

1

This invention relates to chain-stitch sewing machines and more particularly to a thread-controlling mechanism for a thread-carrying looper of a two-thread chain-stitch machine.

A primary object of this invention is to provide a thread-controlling mechanism of simple and inexpensive construction.

It is also an object to provide a thread-controlling mechanism which may be readily adjusted to provide a nicety of control of the looper-thread so as to be suitable for any of a wide range of stitch-lengths, and to be adapted as well for the production of tight firm stitches as for the formation of loose elastic stitches.

A further object is to provide a mechanism of this character, the parts of which are arranged to provide for convenient access thereto, as for threading and adjustment purposes.

With the above and other objects in view, as will hereinafter appear, the invention comprises the devices, combinations, and arrangements of parts hereinafter set forth and illustrated in the accompanying drawings of a preferred embodiment of the invention from which the several features of the invention and the advantages attained thereby will be readily understood by those skilled in the art.

In the drawings:

Fig. 1 is a front elevational view of a portion of a sewing machine embodying the present invention.

Fig. 2 represents a vertical section taken substantially along the line 2—2 of Fig. 1.

Fig. 3 is an enlarged top plan view of the forward portion of the machine bed with the cloth-plate removed to expose the mechanism within the bed.

Fig. 4 represents a vertical section taken substantially along the line 4—4 of Fig. 3, showing particularly the looper driving connections.

The sewing machine of the illustrated embodiment is provided with a frame having a bed 10, which includes a horizontally disposed work-support 11 and vertical front and rear walls 12 and 13 respectively. A standard 14 rises from the bed 10 and supports an overhanging arm which terminates in a head 15. Suitable mechanism is provided in the overhanging arm for imparting vertical reciprocatory and lateral work-feeding movements to a needle bar 16 which is journaled in the overhanging arm 15. The instant invention is adapted for use with either single or multi-needle sewing machines and for convenience is disclosed in the drawings as applied to a machine having two needles 17—17. 50

2

Journalized in suitable bearings in the bed 10 is a bed-shaft 18 which is belt driven, as at 19, in the usual manner. An eccentric pin 20, carried by one end of the bed-shaft 18, is connected by means of a crank link 21 and a rock arm 22 to a looper-carrier 23 which is journaled for oscillation on an axis substantially parallel to that of the bed-shaft 18. A pair of thread carrying loops 24—24 are supported on the looper-carrier 23 for oscillatory loop-seizing and -shedding movements in a vertical plane.

As most clearly illustrated in Fig. 3 of the drawings, a loop spreader periodically engages and spreads the limb of each of the looper threads 15 T which constitutes one limb of the usual thread triangle entered by a respective one of the needles. The loop spreaders comprise a pair of horizontally disposed spreader-fingers 25—25, one for each of the loops 24—24. The fingers are supported at the forward extremity of a spreader-carrying bar 26 which is journaled for endwise sliding movement in lugs 27—27 formed in the bed 10. The rearward extremity of the spreader-carrying bar is formed as a yoke 28 which has a cylindrical pin 29 freely journaled between the arms thereof. The pin 29 is apertured, normal to its longitudinal axis, to slidably receive a cylindrical rock-arm 30 which extends upwardly from a spreader-driving rock-shaft 31. The rock-shaft 31 is journaled transversely of the bed-shaft 18 in needle-bearings 32—32 provided in the front and rear walls 12 and 13 of the bed 10. Oscillatory movements are imparted to the rock-shaft 31 from the bed-shaft 18 by means of an eccentric 33 which is secured for rotation with the bed-shaft by set screws 34—34. Embracing the eccentric 33 is the strap of a pitman 35, which is formed at its upper end with a split-socket 36 entered by a sleeve-ball 37 apertured to slidably accommodate a cylindrical rock-arm 39 which is secured to the spreader-driving rock-shaft 31.

In accordance with the present invention, the spreader-driving rock-shaft 31 is formed with an extension 40 which protrudes through the front wall 12 of the bed 10 and is adapted to actuate the thread-controlling device. To this end, the shaft extension 40 is transversely apertured to receive a cylindrical shank 41 of a thread-controlling arm 42. A clamp-screw 43, which is threaded into a hole 44 formed axially in the rock-shaft 31, provides means for selectively positioning the thread-controlling arm with respect to the shaft extension 40. The thread-controlling arm 42 is bent at its free ex-

tremity to form a laterally extending portion 45 which is provided with a plurality of spaced thread receiving apertures 46, one for each looper thread. Although four apertures are illustrated in the accompanying drawings, it is apparent that any suitable number may be provided, depending upon the number of looper threads to be accommodated.

Cooperating with the thread-controlling arm 42 is a normally stationary thread-guiding member 47 which is slotted, as at 48, to accommodate a fastening screw 49 threaded into the bed 10. At one extremity, the guiding member 47 is formed with a hook-shaped extension defining spaced limbs 50—51, each of which is provided with spaced thread-guiding apertures 52. Preferably, the apertures 52 correspond in number and spacing with the apertures 46 of the thread-controlling arm 42 which is adapted to cooperate with the limbs 50 and 51 in a manner to be described hereinafter. To provide additional means for guiding the looper threads and for preventing snarling thereof, the stationary thread-guiding member 47, at the side opposite the hook-shaped extension, is formed with an ear 53 which is bent outwardly and provided with spaced thread guiding apertures 54.

The path of the looper-threads from a suitable source of supply located above the machine progresses first downwardly along the machine standard through conventional thread-guiding tubes 55 and then to individual tension devices 56. From the tension devices, the looper-threads 52 are directed to the thread-guiding apertures 52 of limb 51 of the stationary thread-guiding member 47, then through the apertures 46 of the controlling arm 42 and next through apertures 52 of limb 59 of the stationary guide. As the threads continue to the looper they are guided by means of the apertures 54 in the ear 52, the usual thread-guide 57 which is fixed to the bed of the machine, the eyelets 58 at the heels of the loopers 24 and finally to the eyes of the loopers in the usual manner.

The thread-controlling arm 42, which receives an oscillatory motion from its connection with the loop-spreader driving rock-shaft 32, engages the looper-threads between the stationary thread guiding limbs 50, 51. The extent of angular movement of the thread-controlling arm 42 is fixed by the eccentric 33 and the rock-shaft driving connections therewith. However, in order to provide for an adjustment of the extent of thread-control, the cylindrical shank 41 of the thread-controlling arm may be selectively positioned lengthwise in the shaft-extension 40 to vary the throw of the laterally extending free end 43 of the arm 42. To accommodate such adjustment of the thread-controlling arm 42, corresponding lateral adjustments of the normally stationary guide 47 may be made by means of the slot 48 and fastening screw 49. In addition, the guide 47 may be selectively adjusted angularly about fastening screw 49 as a pivot in order to change the thread-controlling characteristics of the instant device.

As will be readily apparent to those skilled in the art, the eccentric 33 is timed with respect to the bed-shaft 18 such that the loop-spreader fingers 25—25 occupy an extreme position nearest the standard 14 when the needles are moving downwardly and entering the looper-thread triangles. Moreover, the opposite extreme position of the loop-spreader fingers will occur when the needles are being raised and the loopers are

advancing to enter the needle-thread loops. Since the thread-controlling arm 42 and the loop-spreader fingers 25—25 are both actuated from the rock-shaft 21, the extreme positions of each occur simultaneously; in each instance just after one of the stitch-forming instrumentalities has entered the loop formed by the thread of the complementary instrumentality. Thus, without the necessity for a separate timing adjustment, the present construction provides a controlling device which draws out the looper threads at the proper time in the stitching cycle; i. e. a time when such thread control will cause a minimum of interference with proper loop seizure.

Referring to Fig. 1, the thread controlling arm 42 is illustrated by dotted lines in both of its extreme angular positions. As shown in full lines in Fig. 1, the stationary guide is disposed medianly between the extreme positions of the arm 42. Thus, the thread-controlling arm will draw out a quantity of thread between the apertures 46 and 52 twice during each stitch forming cycle, first as it passes above, and second, as it passes below the apertures of the stationary guide-limbs.

It is pointed out that with the instant invention, the adjustment necessary for any particular application depends upon such factors as stitch length, elasticity of seam desired, etc. As an illustration of the versatility of the instant invention, the normally stationary guide 47 may be adjusted angularly to a position in which the thread-guiding apertures 52 of the spaced units 50 and 51 are substantially aligned with the apertures 46 of the thread-controlling arm 42 in one of its extreme positions. With this adjustment, the thread-controlling arm will draw out a quantity of thread only once during each stitch-forming cycle.

Having thus set forth the nature of the invention, what I claim herein is:

1. In a sewing machine having a reciprocatory thread-carrying needle, a thread-carrying looper complementary to said needle in the formation of chain-stitches, and actuating mechanism for operating said needle and said looper including a looper-actuating shaft, a shiftable looper-thread loop-spreading member, a looper-thread controlling device having a stationary thread-guiding component and a movable thread-engaging element, a common driving member for said loop-spreading member and said thread-engaging element, said driving member being arranged transversely of said looper actuating shaft, and an operative connection between said looper actuating shaft and said driving member.

2. In a sewing machine having a bed, a looper-actuating shaft supported in said bed, and stitch-forming instrumentalities including a thread-carrying chain-stitch looper, the combination of a looper-thread loop-spreading member, a loop-spreader actuating rock-shaft journaled in said bed, operative connections between said looper-actuating shaft and said rock-shaft, and a thread-controlling device comprising a thread-controlling arm secured to said loop-spreader actuating rock-shaft for movement therewith, a thread engaging portion formed on said arm, said portion having an arcuate path of movement about the axis of said rock-shaft, a thread-guiding member fixed to said bed and having spaced thread directing eyelets formed thereon, said eyelets being disposed one at each side of the path of movement of said thread-engaging portion.

3. In a chain-stitch sewing machine of the

type employing a thread-carrying looper and having a bed including a work-support, a looper-actuating bed-shaft journaled beneath said work-support, and a wall depending from said work-support at one side of the bed-shaft, a rock-shaft extending through said vertical wall transversely of said bed-shaft, actuating connections between said bed-shaft and said rock-shaft, an endwise shiftable looper-thread loop-spreader, connections at one side of said wall for actuating said 10 loop-spreader from said rock-shaft, and a looper-thread controlling mechanism including a movable thread-engaging member carried by said rock-shaft at the opposite side of said wall.

4. In a sewing machine having a frame including a work-support and a bed-wall depending from said work-support, stitch-forming mechanism including a thread-carrying chain-stitch looper and a spreader, actuating mechanism for operating said looper including a bed-shaft journaled beneath said work-support and to one side of said depending wall, mechanism for operating said spreader including an actuating shaft extending through said wall transversely of said bed-shaft, and connections at one side of said wall and within the bed for actuating said spreader actuating shaft from said bed-shaft, and a thread-controlling device for said 20 looper-thread disposed on the outside of said depending wall, said thread-controlling device comprising spaced stationary thread-guides, and a movable thread-engaging member operating between said thread-guides, said movable member being carried by said spreader actuating shaft.

5. In a sewing machine having a bed including 35 a work-support and depending front and rear walls, and lower stitch-forming instrumentalities including a thread-carrying looper and a loop-spreader disposed beneath said work-support, a looper-actuating bed-shaft disposed beneath said 40

work-support, a rock-shaft journaled in the depending front and rear walls of the bed transversely of the bed-shaft, an operative connection with the bed-shaft for actuating the transverse shaft, operative connections between the rock-shaft and the loop-spreader disposed intermediate the front and rear walls, said rock-shaft extending through one of said depending walls, and a movable looper-thread controlling arm carried by said rock-shaft externally of said wall.

6. A thread-controlling device for a chain-stitch sewing machine having lower stitch-forming mechanism including a thread-carrying looper, a spreader and a spreader-actuating rock-shaft, comprising a movable arm having one end carried by said spreader-actuating rock-shaft, and a stationary thread-guiding member having a hook-shaped portion providing spaced thread-guiding limbs between which the movable arm is adapted to operate.

7. A thread-controlling device for a chain-stitch sewing machine having lower stitch-forming mechanism including a thread-carrying looper, a spreader and a spreader-actuating rock-shaft, comprising a movable arm having one end carried by said spreader-actuating rock-shaft and having its other end bent to form a thread-engaging portion having thread directing eyes, 25 and a plate-like stationary thread-guiding member having a hook-shaped portion providing spaced thread-guiding limbs between which the movable arm is adapted to operate.
